DESIGN FOR A DOLL HEAD

James Durante and Ernest Hamlin Baker, New York, N. Y., assignors, by direct and mesne assignments, to Umbriago Corporation, New York, N. Y., a corporation of New York

Application February 3, 1945, Serial No. 117,746

Term of patent 14 years

(Cl. D34—4)

To all whom it may concern:

Be it known, that we, James Durante, a citizen of the United States and a resident of the city, county, and State of New York, and Ernest Hamlin Baker, a citizen of the United States and a resident of the city, county, and State of New York, have invented a new, original, and ornamental Design for a Doll Head, of which the following is a specification, reference being had to the accompanying drawing, forming part thereof.

We claim:

The ornamental design for a doll head, substantially as shown.

JAMES DURANTE.

ERNEST HAMLIN BAKER.
